UNITED STATES PATENT OFFICE.

LOUIS BRENNER, OF COLUMBUS, OHIO.

TROUSER SUPPORTER.

Application filed January 16, 1926. Serial No. 81,680.

The present invention is directed to improvements in trouser supporters.

The primary object of the invention is to provide an article of this character so constructed that it can be conveniently secured to the waist of the trousers to form a permanent part thereof.

A further object of the invention is to provide an article of this nature including a belt for engaging the body of the wearer, the belt having combined therewith elements so arranged as to effectively support the trousers without discomfort to the wearer.

15 A still further object of the invention is to provide an article of this character so constructed that the use of suspenders and exterior belts is eliminated.

With these and other objects in view, this 20 invention resides in the novel features of construction, formation, combination and arrangement of parts to be hereinafter more fully described, claimed and illustrated in the accompanying drawing, in which:—

25 Figure 1 is a perspective view of the device.

Figure 2 is a vertical sectional view.

Figure 3 is a partial longitudinal sectional view.

30 Figure 4 is a vertical sectional view through one of the flaps.

The device comprises a belt 1, preferably of stout fabric, the ends of which are provided with adjustably connected buckle elements 2 and 3, respectively, whereby the belt 35 can be conveniently adjusted upon the waist of the user.

Secured to the outer surface of the belt 1 by stitches 4 is a fabric strip 5 of greater 40 width than said belt, there being a canvas stiffening strip 6 of the same width as the strip 5 placed face to face with the strip 5. A plurality of pairs of spaced vertical 45 stitches 7 are applied to the strips 5 and 6, preferably six in number, so as to be equally distributed around the waist of the wearer to provide pockets 8 in which are placed metal plates 9.

Placed in intimate contact with the strip 50 6 is a strip 10, which is of the same width as the strips 5 and 6. The lower edges of the strips 5, 6 and 10 are secured together

by the stitches 4, while the upper edges thereof are secured by stitches 11, which close the upper ends of the pockets 8, the 55 lower ends thereof being closed by the stitches 4. The stitches 11 are also employed to secure the respective strips to the upper edges of the waist to the trousers 12, as clearly shown in Figure 2 of the drawing. 60

The ends of the strips 5 and 6 terminate in flaps 13, which are reduced and consequently of less width than the respective strips. The upper edges of these flaps are secured to the trousers by the stitches 11. 65

It will be observed that the belt 1 is of greater length than the strips 5, 6 and 10 so that access can be conveniently had to the buckle elements 2 and 3. It will be of course understood that the device is fully 70 completed before it is stitched to the waist of the trousers and are made to fit standard size waist lines. However, slight adjustments can be made upon manipulating the buckle elements 2 and 3 should it be desired. 75

In use the belt 1 will snugly engage the waist of the wearer and owing to the fact that the plates 8 are vertically disposed and that the respective strips are secured to the 80 upper edge of the trousers the trousers will be effectively supported from a point above the belt.

Owing to the inherent resiliency of the plates 8 the wearer can bend over and turn 85 or twist without discomfort.

What is claimed is:—

A trouser supporter consisting of a belt, a pair of strips having free end portions 90 with their lower edges stitched to the lower edge of the belt, said strips being disposed longitudinally with respect to the belt and being of less length than the belt, the upper edges of the strips being disposed above the plane of the upper edge of said belt and capable of being secured to the waistband 95 of the trousers, a plurality of pairs of transverse stitches uniting the strips at intervals and providing pockets, and plates arranged in the pockets, as and for the purpose set 100 forth.

In testimony whereof I affix my signature.

LOUIS BRENNER.
